INVENTOR

Anton J. Schmidt
By his wife, J. S.

UNITED STATES PATENT OFFICE.

ANTON J. SCHMIEDL, OF PHILADELPHIA, PENNSYLVANIA.

FABRIC-MARKING MACHINE.

SPECIFICATION forming part of Letters Patent No. 719,516, dated February 3, 1903.

Application filed July 16, 1902. Serial No. 115,754. (No model.)

To all whom it may concern:

Be it known that I, ANTON J. SCHMIEDL, of the city and county of Philadelphia, State of Pennsylvania, have invented an Improvement in Fabric-Marking Machines, of which the following is a specification.

My invention is designed to enable the spacings for buttonholes, buttons, or hooks and eyes to be marked on fabrics with facility and rapidity and to insure the spacings for the buttons or hooks on one piece of the fabric being in proper position with reference to the spacings for the buttonholes or eyes on the other piece.

It is also an object of my invention to enable the spacing-markers to be adjusted with facility to suit variations in the spacings.

In carrying out my invention I employ a rocking frame carrying a series of perforating-fingers adapted to be depressed through the fabric and to form perforations therein corresponding with the desired spacings. Suitable means are employed to enable the perforators to be adjusted to suit the desired spacing, and means may be employed to enable the perforators to apply coloring-matter to the fabric to mark the spacings.

In the drawings, Figure 1 is a plan view of my cloth-marking machine. Fig. 2 is a front elevation of the same. Fig. 3 is a plan view illustrating the marking of the cloth, and Fig. 4 is a cross-section on the line 4-4 of Fig. 2.

a is the base-frame, in the rear of which is pivoted a rocking frame b, carried on a pin b' in uprights b² on the base-frame.

c is a frame carried on the rocking frame b and having its front portion c' extending longitudinally over the base-frame. The frame c is preferably connected with the rocking frame b by a bolt c² and transverse slot c³, by which its position may be adjusted on the rocking frame b.

d represents fingers connected at the rear with the longitudinal portion c' of the frame c by toggles d', to which they are pivotally connected by pivots d², having clamping-heads by which the rear ends of the fingers may be secured to the toggles. The front ends of the fingers d project forward between a longitudinal bar e and a clamping-plate f, carried by the frame c. As shown, the ends of the bar and clamping-plate f are carried by screws e' on the

frame c, and springs e² are inserted between the ends of the bar and plate. This allows greater freedom of movement in the clamp-plate. Clamping-screws f' between the bar e and plate f enable the plate to be drawn up or tightened, so as to clamp the outer ends of the fingers. The heads of the fingers d are provided with eyes g' to receive perforating-needles g, which may be adjusted vertically in the eyes and are held in place by set-screws g².

The front a' of the base-frame a is provided with a series of holes h, adapted to receive the needles g, which are spaced to provide for the variations in the spacing of the buttonhole-marks, &c. In the preferred form the front a' is formed with a longitudinal channel i, the top of which is closed by a scale j, in which are formed the holes h for the perforating-needles, so that the distances between successive perforations may be determined and the needles adjusted accordingly.

By loosening the screws f' to unclamp the clamping-bar f and loosening the screws d² the fingers d may be adjusted to bring the perforating-needles g at the proper distance apart, the same being readily determined by the scale j and perforations h. When the fingers d are properly adjusted, the screws d² are tightened and the fingers are clamped by the adjustment of the clamping-bar f by the screws f'. The cloth is then placed over the scale j and the rocking frame c is depressed, forcing the perforating-needles g through the cloth, and thus marking the points at which the buttonholes are to be formed or the buttons or hooks and eyes are to be attached.

In Fig. 3 I have illustrated the formation of the marks in two pieces of cloth intended to form the opening or placket of a garment, in one of which the buttonholes are to be formed or the hooks attached and to the other of which the buttons or eyes are to be secured. The edges of these two pieces are placed one over the other in the position they should occupy when united and are then placed together over the scale j, and the needles g are depressed and form in each piece the perforations g³, which mark the points at which the buttonholes are to be worked or the buttons, hooks, or eyes to be

attached. When material of dark color is used, it is sometimes desirable that means should be employed to mark the perforations. For this purpose the channel *i* may be filled 5 with chalk or with a liquid coloring substance, which will be taken up by the perforating - needles and applied to the perforations. To enable the needles to more readily take up the chalk or coloring-matter and apply it to the fabric, they may be formed with 10 eyes *g*⁴ or channels, and, if desired, a small cord *m* may be passed through the eye of the needle and formed in a loop about the screw *g*², which will take up the coloring-matter 15 and apply it to the fabric. (See dotted lines in Fig. 2.)

Any means may be employed for depressing the frames *b* and *c* and needles *g*. In the construction shown *n* is a spring acting on 20 the rocking frame *b* and holding it normally in elevated position. The rear end of the frame *b* is acted on by a cam *o*, carried on a shaft *o'*, journaled in brackets *o*² of the base-frame and operated by a pulley *p*.

25 *s* is an adjustable gage, carried by the base-frame *a* to guide the operator in placing the material in position on the scale *j*.

The details of construction shown may be varied without departing from my invention.

30 What I claim as new, and desire to secure by Letters Patent, is as follows:

1. In a fabric-marking machine, the combination of a fabric-support, a rocking frame, a series of independently-adjustable perforating-fingers carried by said rocking frame and extending oversaid fabric-support, whereby they may be adjusted with reference to one another to vary the distance between adjacent perforations formed in the fabric, and 35 means to clamp said perforating-fingers in adjusted position.

2. In a fabric-marking machine, the combination of a fabric-support, a rocking frame, a series of independent perforating-fingers, independently-adjustable connections between each of said fingers and the rocking frame, and a clamp common to all of said fingers to clamp them simultaneously in adjusted position.

45 3. In a fabric-marking machine, the combination of a longitudinal fabric-support provided with a scale, a rocking frame, a series of independently-adjustable perforating-fingers carried by said rocking frame and extending on said fabric-support, whereby they may be adjusted with reference to one another to vary the distance indicated by said scale between adjacent perforations formed in the fabric, and means to clamp said perforating- 50 fingers in adjusted position.

4. In a fabric-marking machine, the combi-

nation of a rocking frame, a series of fingers provided on their outer ends with perforating-needles, toggles pivotally connecting said fingers with the rocking frame, means to clamp said toggles with the fingers, and means to clamp the fingers with their toggles against movement.

5. In a fabric-marking machine, the combination of a rocking frame, a series of perforating-fingers, toggles pivotally connecting the inner ends of said fingers with the rocking frame, means to clamp said toggles with the fingers, and clamping devices carried by the rocking frame to clamp said fingers and 75 toggles against movement after they have been adjusted.

6. In a fabric-marking machine, the combination of a rocking frame, a bar *e* carried thereby and extending longitudinally, a clamping- 80 plate *f* arranged parallel with the bar *e*, a series of adjustable perforating-fingers carried by the rocking frame and projecting between the bar *e* and clamping-frame *f*, and means to adjust said clamping-frame to clamp the 85 perforating-fingers between it and the bar *e*.

7. In a fabric-marking machine, the combination of a longitudinal fabric-support having a recessed portion to contain coloring-matter, a rocking frame, and a series of independently-adjustable perforating-fingers carried by said rocking frame and having their perforators arranged over said recessed portions of the fabric-support, with provision for adjustment with reference to one another to 90 vary the distance between adjacent perforations formed in the fabric and adapted when depressed to receive the coloring-matter and impart it to the fabric, whereby a series of colored perforations may be formed in the 95 fabric, the relative distances between which may be varied.

8. In a fabric-marking machine, the combination of a longitudinal fabric-support having a recessed portion to contain coloring-matter, a rocking frame, and a series of independently-adjustable perforating-fingers carried by said rocking frame and having their perforators arranged over said recessed portion of the fabric-support, and adjusted when depressed to receive the coloring-matter and impart it to the fabric, whereby a series of colored perforations may be formed in the 100 fabric and the distances between said perforations may be varied.

105 In testimony of which invention I have hereunto set my hand.

110 ANTON J. SCHMIEDL.
